(57) **CLAIM**

The ornamental design for an eyelash curler, as shown and described.

DESCRIPTION

FIG. 1 is a perspective view of the eyelash curler showing my new design;

FIG. 2 is a left side view of the eyelash curler, the right side view being a mirror image thereof;

FIG. 3 is a front view of the eyelash curler thereof;

FIG. 4 is a rear view of the eyelash curler thereof;

FIG. 5 is a top view of the eyelash curler thereof; and,

FIG. 6 is a bottom view of the eyelash curler thereof.

The broken line disclosure of the spring is shown for the purpose of illustrating environment and forms no part of the claimed design.
